UNITED STATES PATENT OFFICE.

JOSEPH HOCH, OF MILWAUKEE, WISCONSIN.

CAR-REPLACING DEVICE.

1,250,177.

Specification of Letters Patent. Patented Dec. 18, 1917.

Application filed September 6, 1917. Serial No. 189,941.

To all whom it may concern:

Be it known that I, JOSEPH HOCH, a citizen of the United States, and resident of Milwaukee, in the county of Milwaukee and State of Wisconsin, have invented certain new and useful Improvements in Car-Replacing Devices; and I do hereby declare that the following is a full, clear, and exact description thereof.

10 My invention relates broadly to new and useful improvements in means for returning railway cars and other rolling stock to their tracks after they have been derailed.

In freight yards and at other places where railway tracks terminate, it is necessary to maintain a force of workmen whose sole duty is to replace freight cars and other rolling stock upon the track rails after they have run beyond the ends of said rails. Under present conditions it is very difficult and extremely laborious to replace such rolling stock and it is frequently necessary to secure the services of a derrick. It is therefore the principal object of the present invention to provide a simple arrangement whereby derailed cars may be quickly and easily moved back on to the tracks off which they have run.

15 A further object is to provide a simply constructed device which can be readily formed from old, discarded track rails, and which can be easily attached at the end of any railway track, which is not provided with the usual bumper post.

20 With these and other objects in view, the invention consists of certain novel features of construction, combination and arrangement of parts, which will be hereinafter more particularly described and claimed, and shown in the drawings, wherein:—

25 Figure 1 represents a plan view of a pair of rails forming the end of a railway track, my invention being also shown applied thereto, and

30 Fig. 2 is a detail, transverse, sectional view on the line 2—2 of Fig. 1.

In the drawing the numerals 1 designate the ends of a pair of track rails each together form a railway track standard gage, said track being without the service of a bumper post, which is frequently provided to prevent railway rolling stock from leaving the ends of the rails. Even the strongest bumper post is hardly sufficiently rigid 35 to prevent the derailment of cars when they are moving at an appreciable speed. And

since such bumper posts are easily demolished, their maintenance is rather expensive.

40 My invention on the other hand is comparatively simple and consequently very inexpensive, and although it will not prevent the rolling stock from running off the rails, it will permit the same to be readily replaced when such derailment occurs. It is disposed 45 beyond the end of the track upon ties or sleepers 2 similar to those on which the main track rails are mounted, as is clearly shown in Fig. 1.

45 The device consists of a metallic bar of 50 appropriate length and is bent upon itself substantially midway its ends to form a substantially V-shaped guide rail 3. It is immaterial what form of bar is used so long as it is of sufficient height to form a 55 guide for the wheels of the derailed cars in a manner to be hereinafter more particularly described. It is considered, however, that a track rail of sufficient length and bent into the proper shape will act most 60 advantageously. As shown, the V-shaped 65 guide rail projects beyond the free ends of the track rails 1, the apex of said guide rail being substantially mid way the planes of the track rails. The free end portions of 70 the guide rail are disposed substantially 75 parallel to each other, as shown at 4, these parts being spaced apart a distance somewhat less than the distance between the 80 track rails 1. 85

90 It will thus be seen that the free end portions of the arms of the guide rail are parallel to each other and to the track rails, whereas the inner portions of said arms are inclined from the free end of one track rail toward the opposite track rail. The 95 bends 5 between the two portions of each arm are disposed substantially coincident with the ends of the track rails, and adjacent these bends spaced blocks 6 are disposed between the portions 4 and the adjacent track rails to hold the latter parts in spaced relation. As shown in Fig. 2, the 100 spacing rods 6 have their upper surface disposed below the horizontal planes of the tops of the guide and track rails, said tracks being preferably disposed below the balls or heads of said rails. The outer ends of said blocks may be inclined downwardly, if necessary, to allow the wheels of the rolling 105 stock to more readily ride thereonto.

110 A retaining and strengthening rod 7 ex-

tends through the portions 4 of the arms of the guide rail adjacent the bends 5, through the blocks 6 and the end portions of the track rails 1. This rod has its free ends threaded to receive nuts 8 and 8'; as shown in Fig. 2, these nuts are adapted to engage the outer faces of the webs of the adjacent track and guide rails to clamp the same and the blocks 6 together. The free ends of the track rails 1 are bent outwardly as at 9 to more effectively guide the wheels of the rolling stock.

Other strengthening rods, such as the rod 10, may be used to connect the opposite arms 15 of the guide rail when found to be necessary. Also, various other minor changes in the form and proportion of the various parts of the invention may be resorted to.

Assuming that a railway car has become 20 derailed by running off the ends of the track rails 1 and it is necessary to quickly replace the same, said car is moved in the most convenient manner toward the end of the track. Eventually the wheels of the forward truck engage either one or the other of the inclined portions of the arms of the guide rail, whereupon the continued movement of the car will cause the same to be guided in the proper direction to permit 25 engagement of the spacing blocks 6 by the flanges of said wheels. As the wheels ride up on to these blocks they will engage the 30 end portions of the track rails and be dis-

posed in operative relation therewith. Further movement of the car in the same direction will cause the wheels of the rear truck to engage the guide rail and be guided in the same manner on to the track rail and thus it will be seen that under practically all conditions a derailed car can be readily 40 steered on to the ends of the track rails.

I claim:—

1. A device of the class described, comprising, in combination, the end portions of a pair of track rails, the free ends of said portions being curved outwardly away from each other, a substantially V-shaped guide rail, the free end portions of the guide rail being parallel to each other and to the end portions of the track rails, said parallel portions of the guide rails at their junction with the inclined portions thereof being disposed adjacent the free curved ends of the track rails, and means for connecting the parallel portions of the guide rail and the end portions of the track rails.

2. A device of the class described comprising a bar bent in substantially V-shape, the free end portion of the arms of the bar being parallel, and a bracing rod connecting the arms of the V-shaped bar.

In testimony that I claim the foregoing I have hereunto set my hand at Milwaukee, in the county of Milwaukee and State of Wisconsin.

JOSEPH HOCH.
